RICHARD H. HILTON, OF NEWBERN, NORTH CAROLINA, ASSIGNOR TO
MITCHELL & ALLEN, OF SAME PLACE.

Letters Patent No. 74,822, dated February 25, 1863.

IMPROVEMENT IN MACHINE FOR CLEANING COTTON.

The Schedule referred to in these Letters Patent and making part of the same.

TO ALL WHOM IT MAY CONCERN:

Be it known that I, RICHARD H. HILTON, of Newbern, in the county of Craven, and State of North Carolina, have invented a new and improved Machine for Cleaning Cotton; and I do hereby declare that the following is a full, clear, and exact description thereof, which will enable those skilled in the art to make and use the same, reference being had to the accompanying drawings, forming part of this specification, in which—

Figure 1 is a vertical section of my improved machine.

Figure 2 is a front view of the same.

Similar letters of reference indicate corresponding parts.

This invention relates to an improved machine for cleaning cotton from dust, and consists of a perforated case into which the cotton is fed from the cotton-gin, together with rollers, for the purpose of ejecting the cleaned cotton in the form of a sheet or pressed web, more convenient for packing, with other devices perfecting the whole, as will be hereinafter more fully set forth.

In the drawings, A is the perforated case attached to the delivery-end of a cotton-gin by any suitable means. B represents such delivery-end having the case attached thereto, as shown, so that the ginned cotton passes into the case A, and the current of air produced by the operation of the cotton-gin drives off the dust from the cotton, and thus leaves it in a clean state. The passage of the dust through the perforations is indicated by the red arrows. Rollers E are set in bearings, as shown at the lower part of the case A, and are operated by a belt from some pulley on the gin, which drives the grooved pulley G, keyed on one end of one of the rollers, as shown. The rollers are for the purpose of withdrawing and ejecting the cotton from the case, and in so doing, compress the same in a continuous compact web or sheet, which prevents the cotton from being blown about and wasted by the air-current, and also leaves the cotton in a better state for packing than when the same is in a loose, bulk or pile. The motion is communicated from one roller to the other by any of the devices known for the transmission of motion, as wood or rubber friction-wheels, cog-wheels, or belts; or the rollers themselves may be made to act in contact as friction-wheels, and thus dispense with other gearing. The rollers may be fluted or corrugated, to insure their revolution, if desired. A crossed rubber belt, F, is shown in the drawings for the purpose of transmitting the motion from the upper roller, but, as before mentioned, other means may be employed. In the sides of the case A is a small perforated plate, a, one or more in each side, for the purpose of relieving the revolving brush of the gin of a return current, if found requisite. A screen, D, hinged at the point e of the perforated plate b, is for the purpose of catching the dust as it flies outward in that direction, and thus preventing it from falling upon the issuing cotton shown at m. The dust caught by this screen falls upon the curved surface n, which is left unperforated for that purpose, and from whence the collected dust can be swept off laterally. In practice, the sides of the case may be made of wood, and curved, as shown, for having nailed or otherwise fixed thereon the perforated sheets b and d, which latter may be of tin or other sheet metal, or may be of wire netting, similar to that of which coarse sieves are made. The curve of these perforated surfaces b and d is shown in profile at fig. 1, and this form, although not intended in any way to limit the claim of the invention, is best adapted to its operation, as it enables the entering cotton to be effectively acted upon and cleaned by the current, and also secures the better action of rollers in withdrawing and ejecting the cotton.

My invention is simple, easily constructed, and of small cost, and by its employment the lint-room, so called, as heretofore used, with its attendant disadvantages of waste, space, and expense, is obviated, and the cotton more effectively cleaned than by any mechanism for the same specific purpose. It can be applied to any of the cotton-gins now in use with very small expense.

I claim as new, and desire to secure by Letters Patent—

The S-shaped perforated plate b, the perforated plate d, the side plates having perforations a, drawing-rollers E E, and hinged screen D, all constructed and combined to operate as herein described for the purpose specified.

RICHARD H. HILTON.
